UNITED STATES PATENT OFFICE.

ERNEST H. PEABODY, OF NEW YORK, N. Y., ASSIGNOR TO THE BABCOCK & WILCOX COMPANY, OF BAYONNE, NEW JERSEY, A CORPORATION OF NEW JERSEY.

ATOMIZER OR SPRAYING DEVICE.

1,261,282.

Specification of Letters Patent. Patented Apr. 2, 1918.

Application filed October 4, 1916. Serial No. 123,651.

To all whom it may concern:

Be it known that I, ERNEST H. PEABODY, a citizen of the United States, residing at New York, in the county of New York and State 5 of New York, have invented certain new and useful Improvements in Atomizers or Spraying Devices, of which the following is a specification.

My invention relates to liquid atomizers 10 and more particularly to one for atomizing fuel oil, whereby the oil may be atomized and injected into the combustion chamber of a furnace, in the form of spray, by means of mechanical action induced by pressure. 15 In the accompanying drawing, which illustrates one embodiment of my invention, Figure 1 is a central longitudinal section on the plane of the lines 1—1 of Fig. 2; Fig. 2, an end elevation; Fig. 3, an enlarged 20 central section on the plane of the line 3—3 of Fig. 4; Fig. 4, a half end elevation and half transverse section on the plane of the line 4—4 of Fig. 3; Fig. 5, a view looking toward the inner face of the tip; Fig. 25 6, a side elevation of the tip; and Fig. 7, a transverse section on the plane of the line 7—7 of Fig. 5.

Similar reference numerals indicate similar parts in the several views.

Referring to the drawings the numeral 1 designates the body portion of the atomizer, and 1^x the goose neck in which is formed the inlet port 2 leading to the enlarged strainer chamber 3, the latter having a rear 35 opening 4 closed by a cap 5. Within the chamber 3 is a strainer 6 of any suitable construction, the purpose of which is to remove dirt or foreign matter which may be in the oil before the latter is delivered to 40 the nozzle. The body 1 is reduced at its front end and is threaded to receive the internally threaded portion of a barrel 7. The bore of the barrel has a slight flare at 45 its outer end and over said end is fitted a nozzle 7^x. The latter is formed with a plurality of longitudinal passages 8 extending from its inner conical face to an annular channel 9 formed in its outer face. Seated upon the outer face of the nozzle is a tip 11 50 having a discharge orifice 12 at the apex of a central conical chamber 13. Upon its inner face the tip 11 is formed with a plurality of ducts 14 leading tangentially into the chamber 13 from openings 14', 55 which openings, when the tip is in position,

are located over and communicate with the annular channel 9, thus affording a continuous passage for the flow of the liquid from the barrel 7 to the discharge orifice. The nozzle 7^x may be formed with any desired number 60 of passages 8, four of said passages being shown, with a corresponding number of tangential ducts 14' in the face of the tip.

The forward end of the nozzle is exteriorly threaded to receive a cap 10 having 65 a central opening 10' adapted to receive the central extended portion of the tip and to bear against the tip to clamp it firmly in position upon the face of the nozzle. The face of the cap is concaved at an angle so 70 as to correspond with the concavity in the end of the tip as clearly indicated in Fig. 3.

In operation, the liquid to be atomized enters through the gooseneck 1^x and after passing through the strainer flows through 75 the barrel 7 and is delivered from the passages 8 to the annular channel 9 in the face of the nozzle, through the openings 14' to the tangential ducts 14 to the central conical chamber 13 and thence through the discharge orifice 12. When passing through 80 the central chamber 13 of the tip, the liquid is given a rapid whirling motion, and is projected into the combustion chamber, if 85 oil is the liquid atomized, in a cone of relatively fine spray.

In atomizers of the type herein described, the discharge orifice must be of less area than the combined cross sectional areas of the tangential ducts so as to increase the 90 pressure under the influence of which the fuel is atomized. The areas of said orifice and ducts depend upon the quantity and quality of the liquid fuel to be atomized in a given time and under given condition, 95 such as natural or forced draft. Heretofore, it has been the practice to interpose between the tip and the face of the nozzle a separate member formed with ducts which, when the parts are assembled, are 100 tangential to the wall of the tip chamber. In the use of atomizers, it is frequently necessary when working conditions are changed to substitute a tip having a different sized discharge orifice, or the member having the 105 tangential ducts and, due to faulty assembling of atomizers having discharge orifice in one piece and the tangential ducts in another piece, the proper ratio of the areas of the orifice and the ducts is not maintained. 110

When a tip having a relatively small discharge orifice is assembled with a separate piece having relatively large tangential ducts, the fuel may emerge in a stream and not be properly atomized. Also, when a tip with a relatively large discharge orifice is assembled with a separate piece having relatively small tangential ducts, the atomization of the oil may be excessive and fail to meet the required working conditions. By making a plurality of unitary members, each having a definite area ratio between the discharge orifice and the tangential ducts, I thereby provide means to meet varying working conditions of fuel and pressure and obviate all faulty assembling.

While I have described the ducts 14 as tangential to the wall of the tip chamber 13, I desire to include in said term any degree of eccentricity of the ducts, which will give to the liquid a whirling motion in said chamber.

What I claim and desire to secure by Letters Patent of the United States, is:—

1. In a spraying device, in combination, a nozzle having a channel in the face thereof and passages leading to said channel, a tip having therein a chamber with a discharge orifice and ducts tangential to the

wall of said chamber, said ducts communicating with said channel, and a cap to clamp the tip to the face of the nozzle.

2. In a spraying device, in combination, a nozzle having a channel in the face thereof and passages leading to said channel, a tip having a conical chamber with a discharge orifice at its apex and having in its base a plurality of ducts tangential to the wall of said chamber, and a cap to clamp the tip to the face of the nozzle.

3. In a spraying device, in combination, a nozzle having passages therein, a tip having therein a chamber and ducts tangential to the wall thereof, the end of the tip being concaved, said passages communicating with said ducts, and a cap engaging said nozzle and adapted to clamp the tip thereto, said cap having its outer end concaved to form a continuation of the concaved surface of the end of the tip.

In testimony whereof I have hereunto signed my name in the presence of two subscribing witnesses.

ERNEST H. PEABODY.
